UNITED STATES PATENT OFFICE.

CHARLES F. METZGER, OF NEW YORK, N. Y.

DESIGN FOR THE COVERS OF BOOKS.

Specification forming part of Design No. 6,302, dated December 17, 1872.

To all whom it may concern:

Be it known that I, CHARLES F. METZGER, of the city, county, and State of New York, have invented a Design for Ornamenting the Covers of Books, of which the following is a specification:

The nature of my design is fully represented in the accompanying photographic illustration, to which reference is made.

A represents the outer face of a book or portfolio cover, and B an ornamental border impressed or stamped upon the said cover. The center of the cover may be left plain, or may contain any figures that may be desired. The border consists of a vine-stock running entirely around the sides and top and bottom, with an outward curve at the corners and an inward looped curve at the centers. This stock has several branches bearing leaves, one shooting out from each corner, and twining around the adjacent side, and two at the centers, one running in either direction within the border. Within this outer vine-stock is a second of a similar character, entwining at the centers of the sides, top, and bottom, with the outer vine. This also bears several leaved branches twining about. Pointing into each corner-loop is a spear-head set in a fanciful figure, formed of the petals of flowers. The several corners are also ornamented with two vine-leaves intertwined in a knot with each other and the interior vine-stock, before described, each of these branches bearing upon its end a broad deeply-serrated leaf. This ornamental border, as described, may or may not be surrounded by lines, as shown in the accompanying photograph.

What I claim as my invention is—

A design for ornamenting book or portfolio covers in which the border is composed of vine-stocks with their branches and leaves, and the corner figures, shown and described, substantially in the manner described.

CHAS. F. METZGER.
